CALENDAR

Keith Clark and Archibald G. Mitchell, Ridge-
wood, N. J., assignors to Keith Clark, Inc.,
New York, N. Y., a corporation of New York

Application March 18, 1935, Serial No. 11,542

6 Claims. (Cl. 40—120)

This invention relates to calendars and more particularly to calendars for use on desks.

An object of the present invention is to improve such calendars generally and particularly with respect to providing an improved binder post construction for the paper sheets which will be simple, efficient in use, and durable. Another object of the invention is to provide a desk calendar in which information of a temporary nature may be recorded, yet which will serve also as a permanent record for happenings of importance, the elements thereof being so arranged that the temporary memoranda can readily be removed when no longer useful, without affecting the permanent record. A further object of the invention is to provide a desk calendar in which the legs and binder posts are readily detached from the base so that the calendar as a whole can be placed in a compact container for shipment. Other objects and advantages, as well as the novel details of construction of this invention, will become apparent after a consideration of the description hereinbelow set forth, taken in connection with the accompanying drawing and after a perusal of the appended claims.

A particular embodiment of our improved calendar is illustrated in the accompanying drawing, in which similar reference characters identify similar parts in the several views and in which Fig. 1 is a top view of the calendar; Fig. 2 is a section taken along the line 2—2 of Fig. 1; Fig. 3 is a section taken along the line 3—3 of Fig. 1; Fig. 4 is an enlarged detailed view of one of the binder posts, partly in section, and Fig. 5 is an enlarged detailed sectional view of one of the legs of the calendar.

Referring more particularly to the drawing, the reference character 10 designates the base or stand of the calendar which may be formed of a piece of stamped metal, having sufficient rigidity for the purposes intended. Any suitable metal may be used, such as steel, brass, etc. The metal may also be enameled, nickel plated, chrome plated or made of rust-proof steel. In any event, it is preferable that the surface shall be such as to be resistant against rust and shall be pleasing in appearance. Downwardly extending flanges may also be provided at the side end portions and at the rear end portion of the base to increase the rigidity of the same, to provide smooth edges and to give an impression of greater thickness than the thickness of the sheet metal of which the base is constituted. As shown more clearly in Fig. 3 of the drawing, the base is provided adjacently to the flange on its rear edge portion with a pair of legs 11 which support the base in tilted position. The front edge portion of the base which rests on the table or desk is suitably formed into a trough 12 for the reception of

pencils. A pile of superimposed sheets of paper are supported on the top side of the base and held in position thereon by the binder posts which are designated generally by the reference characters 13. The base 10 has a width which is slightly greater than twice the width of the sheets in the pile so that the paper sheets may be turned over the binder posts 13 as they are used to form two piles on such base, as is clearly shown in Fig. 1.

The pile of superimposed sheets is composed of a plurality of two different kinds of sheets 14 and 15, which are arranged alternately in the pile. The sheets 14 are made from paper stock which has relatively great strength and does not tear easily, while the sheets 15 are made from paper which is substantially weaker than that of which the sheets 14 are constituted. The sheets 14 are each provided with printed matter on both sides, the printed matter on each side of the sheet designating a different day of the year. The printed matter on each of the sheets 14 may be so arranged that when the sheet is positioned on the right hand side of the calendar, as viewed in Fig. 1, the date designated is chronologically one day prior to the date designated on the opposite side of the sheet, so that by turning the sheet over the binding posts to the left hand side of the calendar, the diary page for the following day is presented. The sheets 14 may also have printed matter on each side, dividing the day into suitable time periods, such printed matter preferably extending lengthwise of the sheet adjacent to the left hand edge as viewed in Fig. 1. The sheets 15 are blank but may bear headings indicating that they are intended for temporary memoranda. By reason of the above described arrangement of the sheets, there is always a dated sheet 14 and a sheet 15 on top of the piles. During the day those events which the user desires to keep for his permanent record are noted on the sheet 14, while any data of a temporary nature is noted on the sheet 15. By turning the uppermost sheet on the right hand pile of the calendar over the binding posts, the dated sheet 14 of the following day and a blank page 15 is presented. If a sheet 15 is on the left hand pile at the end of the day, the user may tear such sheet from the calendar, inasmuch as both of its sides have been covered with information of a temporary nature which is no longer useful. Thus, at the end of the year, the pile on the left hand side of the calendar will consist only of the dated sheets 14 which may then be removed from the base and filed away as a permanent record. As the paper constituting the sheets 15 is relatively weak and the binding posts 13 are strong and solid by reason of their construction, as will be herein-after explained, it will be seen that the sheets 60

15 can be readily torn from the calendar with facility. The sheets 14, however, being made of paper which is substantially stronger than that of the sheets 15, cannot be torn so readily from the calendar. The differences in strength of the sheets 14 and 15 is preferably such that the user cannot unknowingly tear a sheet 14 from the calendar by mistake.

The binder posts 13 are positioned near each other on the rear portion of the base so that they will not interfere with the user when he is writing on the sheets 14 and 15; this position of the posts also enabling the sheets 14 and 15 to be readily lifted from the front of the right hand pile and turned. Each of the binder posts 13 comprises a straight tubular female section 16, which is disposed vertically with relation to the top surface of the base 10. As is shown more clearly in Fig. 4, the lower end portion of the female section 16 extends through a perforation stamped out of the base 10 and is provided with an external screw thread 17 which is in threaded engagement with a female thread provided on the inner surface of the downwardly extending flange 18 stamped out of the sheet metal of which the base is constituted. The lower end portion of the female section 16 is securely held in position in the flange 18 by means of the nut 19 which is screwed on the thread 17 and abuts against the lower edge of the flange 18. The height of the female section 16 above the base 10 is approximately equal to the thickness of the pile of superimposed sheets 14 and 15 so that the female sections of such binder posts may serve as guides for placing the pile of sheets in position on the calendar. By loosening the nut 19 and screwing or unscrewing the female section in the threaded flange 18, it will be seen that the height of the female section may be varied to accommodate piles of sheets having different thicknesses. Preferably, however, the unthreaded portion of the female section is made of a length to accommodate a pile of sheets of a standard thickness.

The male sections of the binder posts each comprise a portion 20 which is disposed vertically with relation to the top surface of the base 10, a substantially horizontal portion 21, a vertically disposed portion 22 and a vertically disposed portion 25 which is of smaller cross-sectional area than the portions 20, 21 and 22. The lower end of the portion 20 extends through a perforation in the base 10 and is provided with an external screw thread 23 adapted to receive the nut 24 which is screwed tightly up against the under surface of the base 10 to securely hold the male section in position on the base. The reduced portion 25 is entirely contained within the upper end portions of the female section 16, the upper end of the latter abutting against the shoulder formed by the portions 22 and 25. The diameter of the reduced portion 25 is such that it may be readily inserted into or removed from the female section 16, yet fits sufficiently snug within the latter so that transverse movement between such parts is prevented. The length of the reduced portion 25 is approximately one-half the length of that portion of the female section 16 which rises vertically from the base 10 so that a solid strong connection is formed between the male and female sections of the binder posts. It will be seen that the above described arrangement of the parts provides a simple, strong construction, which in effect forms a permanent part 75 of the base, yet which can be readily disassembled

to insert or remove the calendar sheets. The latter act is accomplished by unscrewing the screw 24 from the thread 23 on the lower end of the portion 20 of the male member and moving the male section upwardly from the base, 5 so that the portions 20 and 25 thereof are slidably withdrawn from the perforation on the base and the female section, respectively. The male and female sections may be made of any suitable metallic material such as steel, brass, etc. While 10 we have shown the horizontally disposed portion 21 of the male member as straight, it will be understood that it may be arcuately shaped or formed in any other manner.

The legs 11 of the base 10 are each secured 15 to the latter by means of a screw 28 which extends through the opening in a downwardly extending or countersunk flange 27 stamped out of the base and is in threaded engagement with a female thread provided on the wall of an axially 20 disposed recess in the upper end portion of the leg. The countersunk portion of the base is so formed that the top edge of the screw 28 is flush with the upper surface of the base 10. The upper end of the leg is provided with an enlarged recess 26 which communicates with the threaded recess and is adapted to receive the flange 27, thereby enabling the upper annular end of the leg to seat tightly against the under side of the base. The diameter of the recess 26 is approximately the same as the diameter of the flange 27 at the under surface of the base so that a snug fit is presented thereby preventing the leg 11 from shifting from its intended position on the under side of the base. This 35 arrangement is also advantageous in assembling the legs on the base because once a screw 28 is engaged with the female thread in a leg it is only necessary to turn the leg without holding the screw as the frictional contact between the 40 side of the screw head and upper side of the flange 27 prevents the screw from rotating while the leg is being screwed into position. Thus the legs may be assembled on the base and secured tightly in position against the under side of the 45 base without the aid of a tool.

While we have illustrated and described a preferred embodiment of the invention, it will be readily understood that various changes in the form, construction and arrangement of the various parts of the invention may be resorted to without departing from the scope of the invention, hence we do not wish to limit ourselves strictly to the structure herein set forth.

We claim:

1. A desk calendar including a relatively rigid base plate having at least twice the area of the calendar sheets to be held thereon and being provided with a perforation having the wall thereof provided with a screw thread and a perforation having an unthreaded wall, a binder post for the calendar sheets comprising a female section disposed vertically with relation to the top surface of the base plate and being provided with a threaded lower end portion adapted to extend through said first mentioned perforation in threaded engagement with the wall thereof, a nut for locking said section in position on the base plate, a rigid male section having a pair of parallelly arranged portions disposed vertically 60 with relation to the top surface of the base plate and connected at their upper ends by a cross piece which is formed integral therewith, one of said vertically disposed portions being longer and having a greater cross-sectional area than the 65

other, said smaller portion being slidably receivable in said female section and said longer portion being slidably receivable in said second mentioned perforation, means for holding said rigid male section securely to the base plate and in locked position with respect to said female section and means for maintaining said base plate in tilted position on a desk.

2. A desk calendar including a substantially flat, relatively rigid base plate, having at least twice the area of the calendar sheets to be held thereon and being provided with a perforation having the wall thereof provided with a screw thread and a perforation having an unthreaded wall, a binder post for the calendar sheets comprising a female section disposed vertically with relation to the top surface of the base plate and being provided with a threaded lower end portion adapted to extend through said first mentioned perforation in threaded engagement with the wall thereof, a nut for locking said section in position on the base plate, a rigid male section having a pair of parallelly arranged portions disposed vertically with relation to the top surface of the base plate and connected at their upper ends by a cross piece which is formed integral therewith, one of said vertically disposed portions being longer and having a greater cross-sectional area than the other, said smaller portion being slidably receivable in said female section and said longer portion being slidably receivable in and extending through said second mentioned perforation to project below the base plate, a nut threadedly engaging with said projecting portion and holding said rigid male section securely to the base plate and in locked position with respect to said female section, a pair of legs for holding said base plate in tilted position on a desk and means for detachably securing said legs to said base plate.

3. A desk calendar including a stamped metal base plate having at least twice the area of the calendar sheets to be held thereon and being provided with a perforation formed by a downwardly extending annular flange stamped out of the metal base and provided on its interior surface with a screw thread and a perforation having an unthreaded wall, a binder post for the calendar sheets comprising a female section disposed vertically with relation to the top surface of the base plate and being provided with a threaded lower end portion adapted to extend through said downwardly extending flange in threaded engagement with the interior wall thereof, a nut threadedly engaging with the projecting lower end portion of said section for locking the latter in position on the base plate, a rigid male section having a pair of parallelly arranged portions disposed vertically with relation to the top surface of the base plate and connected at their upper ends by a cross piece which is formed integral therewith, one of said vertically disposed portions being longer and having a greater cross-sectional area than the other, said smaller section being slidably receivable in said female section and said longer section being slidably receivable in and extending through said second mentioned perforation to project below the base plate, a nut threadedly engaging with said projecting portion and holding said rigid male section securely to the base plate and in locked position with respect to said female section, a pair of legs for holding said base plate in tilted position on a desk and means for detachably securing said legs to said base plate.

4. A desk calendar, including a relatively rigid base plate, having a width at least twice the width of the calendar sheets to be held thereon, so that the sheets may be turned to form two piles, a pile of superimposed sheets comprising sheets made from paper stock of relatively great strength and sheets made from paper stock which is substantially weaker than that constituting the other sheets and arranged alternately in the pile, said strong sheets bearing printed matter to facilitate the recording of information of a permanent nature on said sheets and said weak sheets being adapted to receive data of a temporary nature, said strong and weak sheets each having a pair of perforations positioned closely adjacent to each other along one longitudinal edge of the sheet and at the top portion thereof, a pair of binding posts for securing said sheets in position on said calendar, said binding posts being formed to enable the strong sheets to be turned over to form a separate pile and being sufficiently strong and rigid so that said weak sheets may be readily torn from the calendar as they are used, leaving said strong sheets only as a permanent record.

5. A calendar including a base having a width at least twice the width of the calendar sheets to be held thereon so that the sheets may be turned to form two piles, a pile of superimposed sheets comprising sheets made from paper stock of relatively great strength and sheets made from paper stock which is substantially weaker than that constituting the other sheets, said strong sheets being provided with printed matter on both sides, the printed matter on one side designating a date chronologically one day prior to the date designated on the other side, said strong and weak sheets being alternately arranged in the pile so that as the sheets are turned from day to day to form two adjacently disposed piles on the base there is always a strong sheet and a weak sheet on top of such piles, said strong and weak sheets each having a pair of perforations positioned closely adjacent to each other along one longitudinal edge of the sheet and at the top portion thereof, and a pair of binding posts for securing said sheets in proper position on said base, said binding posts being formed to enable the strong sheets to be turned over to form a separate pile and being sufficiently strong and rigid so that said weak sheets may be readily torn from said calendar as they are used, leaving said strong sheets as a permanent record.

6. A calendar including a sheet metal base, a pile of superimposed sheets on said base, binder posts for said sheets, a pair of legs for holding said base in tilted position on a desk, and means for securing each of said legs to said base comprising a countersunk flange stamped out of said base, a screw extending through the opening in said flange and threadedly engaging with a female thread disposed axially of the leg in the upper end portion thereof and a recess in the upper end portion of said leg adapted to receive the countersunk flange, thereby enabling the upper end of the leg to seat tightly against the under side of the base, the cross sectional dimensions of said recess being approximately the same as the cross sectional dimensions of the flange at the under surface of the base, so that a snug fit is provided at this point.
